GOLF PUTTER

Howard T. Harris, Woodhaven, N. Y.

Application December 6, 1939, Serial No. 307,744

8 Claims. (Cl. 273—79)

This invention relates to golf putters and has for an object to provide an improved construction wherein means are provided to resist or prevent the club from twisting when toeing or heelng.

Another object of the invention is to provide a golf putter having a guide blade formed with an arc-shaped lower surface and a striking blade together with a shaft, the parts being arranged so that the tendency of the putter will be to strike the ball squarely.

An additional object of the invention is to provide a putter formed with a guiding blade and striking blade and a shaft which is swingable from one position to the other so as to accommodate either a right-hand or left-hand putter.

In the accompanying drawing—

Fig. 1 is a side view of a golf putter disclosing an embodiment of the invention, part of the shaft being broken away;

Fig. 2 is a perspective view of the lower part of the putter shown in Fig. 1;

Fig. 3 is an enlarged sectional view through Fig. 1 approximately on the line 3—3;

Fig. 4 is a horizontal sectional view taken on the line 4—4 of Figure 1; and

Fig. 5 is a top plan view of the structure shown in Fig. 1.

Referring to the accompanying drawing by numerals, 1 indicates a shaft of any desired kind having an aperture 2 at one end and through this aperture extends a pin 3 which connects the guiding blade 4 and the striking blade 5. The pin 3 is provided with a head 6 and a bore 7; also the pin includes an auxiliary pin 8 fitting into the bore 7 and provided with a head 9. The auxiliary pin 8 may be screwed into the bore 7 or held therein by a lock pin 10 which extends through the end 11 of shaft 1 and through the entire pin structure. This connects all these parts of the pin and the shaft together so that they will rotate as a unit. The blade 4 is formed of two plates, namely, plates 12 and 13. Plate 13 is provided with a recess 14 adapted to receive head 9 which preferably projects slightly beyond the surface 15 of plate 13. Plate 12 has two flat surfaces and is connected to plate 13 by screws 16 and 17. When these screws are tightened plate 12 will press against the outer surface of head 9, thereby producing a certain friction so that the guiding blade 4 made up of plates 12 and 13 may be freely rotated but will not accidentally move. This friction may be varied by varying the tension of screws 16 and 17. The under surface 18 of blade 4 is rounded so that it will engage the earth in the same way regardless of the angle of the shaft

1. The striking blade 5 is also formed with two plates, namely, plates 19 and 20. These plates are identical in shape with the plates 12 and 13 except that they are rectangular, as shown particularly in Fig. 2. By varying the tension of 5 the screws 21 and 22 the friction between these plates and head 6 may be varied. It will be understood that head 6 preferably extends a slight distance beyond plate 19 so that plate 20 will produce a desired friction for holding the blade 10 in any desired adjusted position in respect to the shaft 1.

In using the putter a person may arrange the parts at the angle shown in Fig. 2, but, if desired, the blades 4 and 5 could be held by the hand and 15 shaft 1 swung over to the other side. This will allow either a right-hand or left-hand putter to use the putter to advantage. When the putter is in use the parts are adjusted so that the bottom line 23 of blade 5 will be horizontal. It will be 20 noted that the blade 5 is much shorter than blade 4 and in a full size device, the full length of the blade 5 may be two inches, although this dimension may be varied. When the line 23 is horizontal and the putter is operated correctly the 25 blade 5 will strike the center of the ball substantially at the point 24 which is the center of the front face of blade 5. This will result in the ball taking a straight course toward the cup. The striking surface 25 of blade 5 is restricted in comparison to the side surface of blade 4 and by reason of the position and arrangement of parts prevents the club from twisting in the hands due to toeing or heelng the ball as is sometimes true when a blade putter is used. Because of the 30 restricted hitting area of surface 25 the club is less apt to twist in the back swing, and, therefore, a more accurate putt is assured. The construction also presents a balanced arrangement and by being balanced four ways on the shaft, the club has 35 40 a much better feel than a blade putter. An adjustability of the blades permit the user to adjust the blades to suit his own style of putting. It will also be noted that regardless of the adjustment of blades 4 and 5, their side surfaces 45 remain parallel and extend at right angles to the line of the proposed putt. In forming the blades 4 and 5, preferably they are formed of metal, as for instance, steel, but, if desired, could be formed of other material without departing from the 50 spirit of the invention. Also, when using the putter the blade 5 preferably strikes the ball at point 24, although it may strike the blade at other points on the surface 25 and produce good 55 results.

I claim:

1. A putter including a shaft, a guide blade, a striking blade and means for connecting said blades and shaft together so that either blade or shaft may rotate independently.
2. A putter including a pair of spaced substantially parallel blades, a pin rotatably connected to both of said blades and a shaft having one end rigidly connected to said pin.
10. 3. A putter including a guide blade, a striking blade, means for connecting said blades in spaced relation, said blades being independently rotatable, and a shaft having one end mounted between said blades rigidly secured to said means and rotatable in respect to the blades.
20. 4. A putter including a guide blade, a striking blade appreciably shorter than the guide blade and spaced therefrom but with side surfaces parallel with side surfaces of the guide blade, means for securing said blades together, said means permitting said blades to rotate in respect to each other and a shaft having one end rotatably mounted between said blades.
25. 5. A putter including a guide blade, a striking blade, a pin structure rotatably connecting said blades, said pin structure being formed with frictional members for preventing free rotation of said blades and a shaft having one end rigidly secured to the pin structure.
30. 6. A putter including a guide blade formed with an arc-shaped ground engaging edge, a striking blade of appreciably less length than

said guide blade, said striking blade being positioned centrally of said guide blade but spaced therefrom, a pin structure connecting said blades, said pin structure being independently rotatable in respect to both of said blades and a shaft having one end rigidly secured to said pin structure whereby said shaft may be swung to accommodate both right and left hand putters.

7. A putter including a guiding blade having an arc-shaped ground engaging edge, a striking blade appreciably shorter than the guiding blade, a member for connecting said blades in spaced relation, said blades being independently rotatably connected with said member, means for providing friction between said blades and said member and a shaft rigidly secured at one end to said member between said blades.

8. A putter including a guiding blade having an arc-shaped edge, a striking blade appreciably shorter than the guiding blade, a member extending from the center of said guiding blade to the center of said striking blade for rotatably connecting the blades so that they may rotate independently of each other and independently of said member, said blades being connected together in spaced relation, said member at each end having an enlarged head, means for varying the tension of the heads in respect to said blades and a shaft having one end rigidly secured to said member between said blades.

HOWARD T. HARRIS.
